PILOT BURNER GUARD

Albert C. Schickler, Cleveland, Ohio, assignor to
 The Ajax Thermostatic Controls Co., Cleveland,
 Ohio, a corporation of Ohio

Application November 19, 1945, Serial No. 629,357

3 Claims. (Cl. 158—113)

1

The general object of this invention is to protect the flame of a pilot light from drafts and from violent air disturbances such as result from extinguishing or lighting the main burner, and also to prevent foreign particles such as soot, scale and the like from getting into the burner.

Another object is to retard or impede the velocity of the gas flame, when the gas pressure supply thereto rises to higher than normal, thus preventing self-extinguishing of the flame. At the same time, it is desirable for more effective burning that the velocity pressure be translated into a comparatively static pressure producing an evenly burning flame.

A simple form of pilot burner or pilot "light" which is economical of gas, provides a desirable mixture and a hot flame is that of the Bunsen burner type.

In such burners variations in gas pressure and velocity of flow may result in breaking the continuity of the flame, thus extinguishing it. It is desirable, and therefore one of the objects of this invention, to retard the high velocity of the gas and air mixture for the flame.

A specific object is to spread the flame as to protect it against extinction.

Another object is to provide such a device for use with a standard form of simple pilot tube burner, and which device may be very cheaply manufactured, be capable of convenient assembly with the burner tube, and which may hold it self in position by spring tension.

A preferred form of my invention is illustrated in the accompanying drawings, in which

Fig. 1 shows the present invention associated with the pilot burner;

Fig. 2 is an enlarged axial section through the pilot burner, with the present invention attached thereto;

Fig. 3 is a top plan of the same;

Fig. 4 is a sectional detail on the line 4—4 of Fig. 3;

Fig. 5 is a perspective view showing the spring supporting element before applying the cap member.

In Fig. 1, B designates the main burner such as used for a hot water tank—not shown. This view is merely as illustrative of any use of such pilot burners.

A gas supply line P leading to the vicinity of the burner is shown as provided with threads to receive a threaded nipple 16 at the lower end of the burner tube 12 open at its upper end and provided with air openings 14 appropriately positioned above the opening 15 for the gas inlet jet.

2

As normally used, this burner is placed closely adjacent to the orifices of the main burner B, and its flame normally rises substantially above the open end of the tube 12. When so used various disadvantages result.

A serious difficulty is that of the violent disturbances of air and gas resulting when the main burner is shut off and its flame is suddenly extinguished with a violent reaction such as results from the explosive burning of gas remaining in the chamber of the main burner. This disturbance often extinguishes the flame of the pilot, and unless provision is made for automatically relighting the pilot, which provision is often expensive and not always reliable, the main burner may be turned on and remain on in an unlighted condition.

Extraneous sudden drafts may extinguish the unprotected pilot flame, particularly when this flame is burning either very weakly due to low gas pressure, or is burning at a higher position than normal due to greater mixture stream velocity resulting from high pressure from the jet 15.

In such conditions the pilot flame is particularly vulnerable to being extinguished. Various guards and re-lighting devices have been devised, obviously adding expense and which are not always found to be reliable.

As indicated in the foregoing stated objects, the present invention consists of an exceedingly simple and yet very effective means for protecting the flame from such extinguishment.

I have found it important to retard the flame velocity, and also desirable to spread the flame as is indicated by the broken lines at F in Figs. 1 and 2. In so retarding the mixing stream for the flame it is still essential to maintain sufficient mixture and speed of flow for uniform burning around the canopy 25.

One of the present difficulties is that of acid attacking the burner tube, now usually made of brass, and resulting from condensate of flue products falling from the surfaces above.

In practice, the tube of the burner is often eaten away in a short time by the effects of such condensate. Soot and condensate form a carbon substance, sometimes completely blocking the gas burning and mixing passage of the burner.

To avoid these difficulties, various devices such as special acid resisting tips, for example, lava tips, are mounted at the top of the burner. However, these increase resistance to the flow and adversely affect the character of the flame.

A preferred embodiment of my invention consists of a dome-shaped cap, preferably quite flat,

forming the canopy 25 and having an inturned flange 26 adapted to receive a supporting loop 30 of the burner engaging and carrying member.

This loop is substantially circular and formed to require being compressed slightly to permit it to be inserted inside of the flange 26 after a manner well known in connection with certain forms of button heads, such as campaign buttons, or the like.

It is important that the canopy 25 be properly spaced above the open end of the burner tube 12, and that it may also be securely held in the position shown in Figs. 1 and 2. To this end I form a tube engaging portion 35 integral with the loop 30 and having an end extension 38 engaging the top of the tube 12.

Describing this supporting element more in detail, I prefer to form the circular head portion 30 and the tube engaging portion 35 of one continuous piece of wire. As shown, the loop of the head portion merges with an inward radially extending arm 31, substantially in the plane of the loop 30, and from which the wire bends downwardly forming a leg 35 substantially right angles to the plane of the head loop. The wire continues in a return bend at 36, and then upwardly forming a leg 37 still in a plane substantially normal to the head loop. The end of the leg 37 has a short portion turned sharply outwardly at 38 to form a shoulder or abutment for engaging the upper end of the tube.

As formed, the leg 37 carrying the hooked end 38 is preferably sloped outwardly from the position it takes when in the tube, in order to give a firm gripping or spring action for engaging the tube.

In Fig. 5, 37a indicates in broken lines the position of the arm 37 parallel with the upright leg 35, and the approximate bending or spring action effect of the loop is from the position of the leg 37 shown in solid lines.

The width of the loop 35, 36 and 37 and the comparatively straight legs forming its sides causes an effective tight engagement across the diameter of the upper end of the inside of the tube 12.

The nose portion or bend 36 facilitates the insertion into the tube, and the length below the limiting hook 38 may be approximately one half of the distance from the mixer air openings 14 to the upper end of the burner tube. When in its supporting position, the tube engaging loop lies in the plane normal to the plane of the cap loop 30, and the length of the arm 31 is such as to center the loop 30 and the canopy over the burner tube.

The distance from the lower side of the hook 38 to the loop 30 establishes the space, between the tube and flange of the canopy, from which the spreading flame mixture stream flows and is determined for most effective burning with relation to the usual ranges of gas pressure.

The canopy 25 is preferably made of a stainless steel disk to effectively resist corrosion from condensate and also to resist heat. The supporting wire, being protected by the canopy, may be formed of any metal capable of retaining its spring action under fairly high temperatures. In practice stainless steel wire is preferred.

The cap 25 may be formed of very thin sheet material for purposes of economy. The size of the wire is determined largely by its relative diameter to that of the inside of the burner tube, it being desirable to avoid causing eddy currents which may impair the burning of the flame. Thus,

in a burner tube of approximately one quarter inch inside diameter, about one thirty-second of an inch diameter wire is satisfactory, and is sufficient to hold the cap rigidly in its spaced and horizontal position above the burner.

It will be seen that the supporting wire and flanged caps may be formed and assembled in quantities, and may be conveniently inserted into the burner, whereupon the spring action forces the relatively straight side legs 35 and 37 into engagement with the tube, and across its diameter, and to hold the carrying leg 35 against the wall of the tube for a distance sufficient to prevent tipping of the cap.

In inserting the supporting loop, obviously pressure of the thumb on the cap 25 contracts the bend 36 and the inward movement is limited when the hooked end 38 strikes the top of the tube. Thereafter and until removal, the parts are held firmly in this operative position by spring action of both the cap loop and the tube loop.

As above indicated, a serious source of trouble is that of particles of scale and soot falling from surfaces above the pilot burner. The condensate, as stated, is destructive to the burner tube, and the size of the protecting canopy should provide sufficient overhang to afford adequate protection from condensate drippings and falling particles.

A cap approximately five-eighths of an inch in diameter for a burner tube of half that diameter has been found satisfactory.

From the foregoing description, it will be seen that I have provided a very simple form of guard which has the advantages of being formed by standard practices, i. e., punching and flanging a disk and by wire forming, and which when assembled may be inserted with ease, and thereafter may be retained securely in operating position.

Various modifications of the cap and wire support, with its spring action and limiting means establishing the flame mixture passage, may be made without departing from the spirit and scope of my invention as defined in the appended claims.

Having thus described my invention, what I claim is:

1. A burner guard for an upright pilot burner tube comprising a disk-like canopy of a diameter larger than the tube and a support for holding the canopy concentrically of the tube and spaced above the same, said support comprising a single strip of wire formed into a horizontal loop and a downwardly extending arm, a round nose portion and an upwardly continuing arm provided with an outward projection, the arms forming a loop in a plane at right angles to the plane of the first named loop, said projection being spaced from the plane of the first loop, and means on the disk member for engaging and holding the first loop under compression.

2. A guard for an upright pilot burner tube comprising a button cap substantially larger in diameter than the diameter of the tube and having an inturned flange, a wire support having a loop yieldingly engaging within the flange, and having a horizontal portion extending toward the center of the loop and integral with a downwardly extending loop adapted to project into and yieldingly engage the interior of the tube, and a shoulder formed on the latter loop engaging the top of the tube to space the flanged cap member above it to provide flame burning space between the tube and cap member.

3. A guard for an upright pilot burner tube comprising a flanged cap substantially larger in

diameter than the diameter of the tube, a wire support having a loop yieldingly engaging within the flange, an integral downwardly extending loop adapted to project into and yieldingly engage the interior of the tube, and a shoulder formed on the latter loop engaging the top of the tube to space the flanged cap member in a horizontal position above the tube to provide flame orifice space between the tube and cap member.
